FLEXIBLE ROD DRIVER

Lothar W. Schoensiegel, Chicago, Ill.

Application July 26, 1946, Serial No. 686,583

5 Claims. (Cl. 74—421)

1

This invention relates to rod drivers, and more particularly to a driver having a driving motor to rotate the rod, as a flexible rod of the type used for cleaning out pipes.

One feature of this invention is that it provides an improved rod driver; another feature of this invention is that it provides a flexible rod driver allowing straight extension of the rod through the rod driver and on both sides of the rod driver, with no bending or kinking of the rod; a further feature of this invention is that it provides a flexible rod driver adapted to include means for reducing the speed of rotation of the rod relative to the speed of the drive means; yet another feature of this invention is that it provides a rod driver having removable rod gripping means; still a further feature of this invention is that it provides a flexible rod driver having quick acting rod gripping means adapted to grip and release the rod being driven without the operator stopping the driving motor; still another feature of this invention is that it provides a rod driver having latch means for releasably locking the rod gripping means. Other features and advantages of this invention will be apparent from the following specification and the drawings, in which:

Figure 1 is an elevation of a rod driver constructed in accordance with my invention, showing said rod driver in operation; Figure 2 is a sectional view of the rod driver, taken on the line 2—2 of Figure 1, with the flexible rod removed; Figure 3 is a vertical section on the line 3—3 of Figure 2; Figure 4 is a vertical section on the line 4—4 of Figure 2; and Figure 5 is a vertical section on the line 5—5 of Figure 2.

Prior to my invention electric rod drivers used for the purpose of driving a flexible rod into a sewer, drain pipe, or other enclosure in order to clean or remove obstructions therefrom comprised devices similar to the conventional electric drill. A device of this type has several disadvantages preventing its efficient operation in cleaning such a sewer or drain pipe. For example, in such a device the flexible rod which is used for cleaning the sewer or drain pipe is brought into the driver casing through the side or bottom of the device, is turned at approximately right angles, and is brought out through the front end of the casing. Such a construction has been heretofore thought necessary in order to bring the rod into operable relation with the drive motor which is located in the driver casing and is utilized to rotate the rod. Obviously such a construction is disadvantageous, for at least a portion of the rod immediately

2

behind the point of entry into the casing is disposed transverse to the direction of rotation of the drive motor, and consequently the portion of the rod behind the rod driver will thresh and whip about.

In operation, as the rod advances into the sewer or drain pipe it is necessary periodically to release the grip of the rod driver on the rod and to move the rod forward through the rod driver in order to obtain a new grip farther back on the rod. Another disadvantage to the efficient use of such a rod driver has been that each time before such periodic action takes place it has been necessary to stop the drive motor, with a consequent loss of time while waiting for the motor to slow down and stop, and another loss of time while waiting for the motor to gain speed after the new grip has been obtained and the motor has been started again.

20 I have devised and am here disclosing an improved rod driver which overcomes these and other disadvantages inherent in prior rod drivers. My improved rod driver is so constructed that the rod being driven extends straight through the 25 driver casing and straight out in front and behind the driver casing, thus eliminating all twists, turns, or kinks in the rod, and doing away with threshing and whipping of the rod behind the rod driver. My new rod driver also incorporates 30 novel releasable rod gripping means comprising a quick acting chuck which may be simply and efficiently operated to release the rod so that the rod driver casing can be moved forward or backward on the rod and a new grip obtained, all without stopping the drive motor. Consequently the 35 operator using my new driver saves a great deal of time as the rod is advanced into the sewer or drain pipe, for when it is desired to obtain a new grip at a different place on the rod, the operator 40 merely manually operates a lever to free the rod, moves the rod driver to the new position on the rod, and operates the lever back to its first position to obtain a new grip on the rod. The drive motor need never be turned off during the entire 45 cleaning operation.

In addition, my invention incorporates a removable chuck which may be readily taken off of the casing, allowing the substitution of a conventional chuck, as for example a Jacobs drill chuck, and the rod driver may then be used as a drill or other rotator.

Referring now to the drawings, my improved rod driver is shown as comprising a casing 10 having ventilating holes or slots 11 and a supporting handle 12, which is here shown as being a

pistol type handle with a conventional spring biased so-called "dead man" type on-off switch 13 for the drive motor. Also extending from the casing behind the handle 12 is the conventional reversing switch 14 for the drive motor. The opening 15 is for a conventional line cord (not shown) for supplying power to the motor.

The casing has two oppositely placed openings 16 and 17 therein, one at each end of the casing, for receiving the rod to be driven. Such rod may comprise a conventional double coiled flexible shaft as is shown at 18 in Figure 1, and extends straight through the casing by means of the oppositely disposed openings 16 and 17, and straight out behind the casing. The conventional cutting tool or cutting head 19 of the rod is shown in operative position as extending into a sewer or drain pipe 20.

Within the casing is the rod guiding means comprising the tubular shaft 21 rotatably mounted in axial alignment with the oppositely placed openings 16 and 17, and adapted to receive and guide the rod straight through the casing without any bending or twisting. The shaft is mounted in bearings 21a and 21b, and at its left hand end (in Figure 2) the shaft extends through the opening 16 and terminates in an enlarged portion 22 externally threaded at 23 for the reception of the removable chuck as will be hereafter explained. Mounted coaxially with the shaft 21 is the drive motor which may be an A. C.—D. C. reversible motor comprising the field coil 24 and the armature 25, and having a hollow drive shaft 26 which surrounds a portion of the tubular rod guiding shaft 21 and is coaxial therewith, but is not directly fixed thereto and is rotatable in the bearings 27 and 28.

Since the speed of rotation of the motor is much greater than the desired speed of rotation of the flexible rod 18, the rod driver incorporates speed reducing means comprising a balanced gear reduction drive. The pinion 29 is fixedly mounted on the drive shaft 26, and on opposite sides of the drive shaft said pinion meshes with the gears 30 and 31. Gear 30 is keyed to the shaft 32 which is adapted to rotate in bearings 32a and 32b and has fixedly mounted thereon the pinion 33 which in turn meshes with and drives the gear 34 which is keyed to the tubular shaft 21 at 35. Similarly the gear 31 is keyed to the shaft 36 which is rotatable in bearings 36a and 36b and fixedly carries the pinion 37 which meshes with the gear 34 at a point opposite from the pinion 33, and assists in driving the shaft 21 in such manner that the drive strain is equally distributed on opposite sides of said shaft. In the rod driver illustrated in the drawings, access may be had to the speed reducing means for greasing or repair by removing the studs 37a.

The chuck, which is indicated generally at 38 in Figure 1, is adapted to be removably mounted on the enlarged portion 22 of the tubular shaft 21 for rotation with said shaft, by means of the internally threaded portion at the end of the chuck body member 39, the threads of which cooperate with the threads 23, and by means of the set screw 40. The chuck includes a bore 41 adapted to slidably receive the rod 18, said bore being coaxial with the tubular shaft 21 throughout the entire length of the chuck from the threaded portion 39 to the nose piece 42. Extending within the bore intermediate its ends are the rod gripping means or chuck jaws comprising the three rod gripping members 43a, 43b, and 43c, each having an undulating or wavy surface

44 within the bore in order to obtain a better grip on the rod 18. A circular spring wire 45 passes through an opening in each gripping member and constantly urges the gripping members outward. The outer end or surface of each gripping member is beveled as shown at 46 and cooperates with the beveled surface of the slidably mounted pressure member 47 in such manner that if the pressure member 47 is thrust forward (to the left in Figures 1 and 2), the gripping members 43a, 43b, and 43c move inwardly into the bore 41, and the undulating surfaces 44 obtain a firm grip on the rod 18 so that said rod rotates with the tubular shaft 21. If the pressure member 47 is moved backward, the spring 45 urges the members 43a, 43b and 43c outwardly away from the rod 18, and the rod is no longer bound to the tubular shaft 21 and no longer rotates with said shaft. As shown best in Figures 2 and 4, the gripping members 43a, 43b, and 43c are held in place by the nose piece 42 which is keyed to the member 39 by means of the taper pin 42a.

The apparatus for sliding the member 47 forward and backward consists of a coupling and lever arrangement comprising the ring member 48 rotatably mounted on ball bearings 49 in an annular groove 50 in the pressure member 47, the link members 51 each pivotally mounted at the forward end on opposite sides of the ring 48 by the studs 52 and each pivoted at the rear end on a branch of the biforked L-shaped operating lever 53. The branches of the biforked operating lever 53 are eccentrically pivoted on opposite sides of the casing by the studs 54, and the free end of such lever is formed into a handle 55 adapted to be grasped by the operator.

The apparatus for operating the gripping means in my improved rod driver is completed by a latch arrangement for releasably holding the lever member 53 in any desired position, such latch arrangement comprising the toothed arm 56 pivotally mounted on a bracket 57 attached to the casing 10 and urged toward the handle 55 of the lever 53 by a spring 58. The latching mechanism comprises the latch member 59 adapted to cooperate with the teeth of the arm 56 and operated through the rod 60 and the lever comprising the link 61 and the trigger member 62. If desired, a spring may be inserted in the handle 55 to hold the latch member 59 in engagement with the teeth on the arm 56 except when the trigger member 62 is pressed.

It will be seen that if the operator of the rod driver pulls the handle 55 to the right after releasing the latch (speaking with respect to the position of the parts as reviewed in Figure 1), the biforked lever 53 will pivot about the studs 54, and since the lever is eccentrically mounted, the link 51 will move forward or to the left. This movement is transmitted through the ring 48 to the pressure member 47, and the gripping members 43a, 43b, and 43c are caused to move into the bore 41 and grip the rod 18. Since the gripping members are connected through the chuck body member 39 to the tubular shaft 21, the rod 18 will now rotate with the tubular shaft when the motor is running, the operator pushing forward to provide a force tending to move the rod into the pipe as it rotates. As the rod 18 advances into the pipe 20 it will become necessary to slide the rod driver back on the rod 18. In order to accomplish this it is not necessary, as it has been heretofore, for the operator to turn the motor off, for if the operator pushes the handle 55 forward or to the left, the pressure

member 47 will move backward, thus freeing the gripping members, which will be urged outwardly by the spring 45, and will release the rod. The rod will now cease rotating, and will be slidable in the tubular shaft 21 and the chuck 38, and the rod driver may be moved back to a new position on the rod and a new grip on the rod obtained, whereupon the rod would again be rotated by the motor and pushed forward by the operator. In operating my improved rod driver, the operator is not subjected to the inconvenience and danger heretofore present in rod drivers, because the rod extends straight through my new rod driver and straight back therefrom, and the rod does not whip and thresh as it is rotated.

While I have illustrated and described certain modifications of my invention, it is to be understood that it is capable of many modifications. Changes, therefore, in the construction and arrangement may be made without departing from the spirit and scope of the invention, as disclosed in the appended claims.

I claim:

1. In rod driving apparatus having rotatable rod guiding means and drive means for rotating said rod guiding means, lever operated apparatus of the character described for selectively gripping and releasing the rod to be driven, such lever operated apparatus including gripping means rotatable with said rod guiding means an operating device comprising a pivotally mounted member, and coupling means including at least one link eccentrically pivoted on said operating device and connecting said operating device with said gripping apparatus.

2. Flexible rod driving apparatus of the character described, including: a casing having oppositely placed openings therein for receiving the rod to be driven; a longitudinally straight rotatable tubular member axially aligned with said openings and adapted slidably to receive the rod to be driven; a reversible motor for rotating said tubular member, said motor having a hollow drive shaft surrounding at least a portion of said tubular member and coaxial therewith; speed reducing means operatively connecting the drive shaft with the tubular member; gripping apparatus including a plurality of lever operated, slidably movable jaws rotatable with said tubular member for selectively gripping and releasing the rod to be driven and a latch for releasably locking said jaws in desired positions.

3. In a rod driver having a casing, rod guiding means, and rotatable drive means, apparatus of the character described, including: rod gripping means comprising movable jaws rotatable with said drive means; means for causing said jaws selectively to grip and release the rod to be driven, such means comprising a lever operating

member eccentrically pivoted on said casing and a link pivoted on said lever member and operatively connecting said lever member with said gripping means; and latch means for releasably locking said lever member, said latch means including a pivotally mounted member adapted to engage said lever member.

4. In a rod driver having rod guiding means adapted to have a conventional chuck mounted thereon, and having rotatable drive means, apparatus of the character described, including: gripping apparatus including at least one slidable pressure member, at least a portion of said apparatus being rotatable with said drive means and said gripping apparatus being mounted on said guiding means in a manner permitting its ready removal therefrom; lever means for causing said gripping member selectively to grip and release the rod to be driven; and means for readily removably connecting said lever means to said slidable pressure member.

5. In a rod driver having rod guiding means and rotatable drive means, apparatus of the character described, including: gripping apparatus rotatable with said drive means, said gripping apparatus comprising a body member threadably mounted on said guiding means, at least one gripping member carried by said body member, and a pressure member slidably mounted on said body member; coupling means having an external anti-friction connection directly to said pressure member; lever means for causing said gripping means selectively to grip and release the rod, said lever means being pivotally mounted on said guiding means and being detachably connected to said coupling means to permit ready removal of said gripping means from said guiding means; and latch means for releasably locking said lever means.
